No. 698,852.

Patented Apr. 29, 1902.

G. B. PICKOP.

SLIDING DOOR.

(Application filed Jan. 15, 1902.)

(No Model.)

UNITED STATES PATENT OFFICE.

GEORGE B. PICKOP, OF NEW BRITAIN, CONNECTICUT, ASSIGNOR TO P. & F. CORBIN, OF NEW BRITAIN, CONNECTICUT, A CORPORATION OF CONNECTICUT.

SLIDING DOOR.

SPECIFICATION forming part of Letters Patent No. 698,852, dated April 29, 1902.

Application filed January 15, 1902. Serial No. 89,826. (No model.)

To all whom it may concern:

Be it known that I, GEORGE B. PICKOP, a citizen of the United States, residing at New Britain, county of Hartford, State of Connecticut, have invented certain new and useful improvements in Sliding Doors, of which the following is a full, clear, and exact description.

My invention relates to operating devices for sliding doors whereby motion imparted to one will be mechanically transmitted to the other to cause it to move in the opposite direction.

The invention is of great utility in connection with street-car doors and the like.

The object of my invention is to provide an operating mechanism to accomplish the above-referred-to purpose, which mechanism shall be simple, durable, and effective.

In the drawings, Figure 1 is an elevation of my invention, showing portions of a pair of sliding doors. In this view a portion of the mechanism is broken away for convenience of illustration. Fig. 2 is a plan view of the part shown in Fig. 1. Fig. 3 is a relatively enlarged plan view of details of construction, said view being partly in section. Fig. 4 is a relatively enlarged elevation of another detail of construction. Fig. 5 is a plan view of a blank for a rack of my improved form. Fig. 6 is a cross-section of the finished rack.

A A' are doors.

B B' are what I shall call "shive-cases."

C C' are shives or grooved rollers.

C² is a track located above the doors and upon which the grooved rollers or shives C C' rest, so that the doors A A' may be slid back and forth in the usual way.

The purpose of my invention is to provide a simple, durable, and effective mechanism whereby both doors will be opened or closed simultaneously in the event either door is opened or closed. By my improvement there is little or no lost motion and there is little or no danger of the doors becoming jammed or the apparatus broken.

D D' are toothed racks carried by the doors A A', respectively. These racks D D' are preferably connected to the doors at some in-

visible point—for example, within the casing above the door. One convenient place for locating the connection is illustrated in the drawings, in which E E' are pivots carried by the shive-cases B B'. In the preferred form these racks are loosely pivoted, so that they may have sufficient play or independent movement to avoid danger of jamming and to permit the said racks to mesh properly with a pinion F. By preference the pinion F is barrel-shaped and is carried in a cage G. This cage G is loosely supported, so that it may slide transversely in a guideway in a bracket H, which is secured at any suitable point, preferably within the casing above the door and in proper alignment with the racks D D'.

I I' are antifriction-rollers carried by the cage G. The rack D passes between the antifriction-roll I and the pinion F. The rack D' passes between the antifriction-roll I' and the pinion F, and the adjustment of the antifriction-rollers II' is such as to hold said racks in proper mesh with the said pinion. The sides or posts H' H' of the bracket are sufficiently narrow so that the teeth of the racks D D' will not engage with the same as the doors are opened or closed.

I preferably form the racks D D' of sheet metal, in which teeth may be formed at the edges of a blank, as shown in Fig. 5, which edges are turned up so as to form a U-shaped or channel bar, the upright edges of which provide the teeth of the rack. (See Fig. 6.) Such a rack has many advantages. It is extremely light, cheap, and strong, and because it affords a positive two-point bearing it will not chatter in use, but runs upon the pinion in a practically noiseless manner.

Obviously a variety of modifications may be made without departing from the spirit of my invention. It would require merely the skill of the mechanic to reverse the parts and locate the operating devices in the casing or a space below the doors instead of in the casing above the doors, as shown.

What I claim is—

1. An improvement in sliding doors, comprising a pair of doors, a rack carried by each

of said doors, a swinging connection therefor, and a barrel-shaped pinion meshing with said racks whereby the motion of one is transmitted to the other, and a carrying device for said pinion.

2. An improvement in sliding doors, comprising a pair of doors, a pivoted rack carried by each of said doors, and a pinion meshing with said racks whereby the motion of one is transmitted to the other, and a carrying device for said pinion.

3. An improvement in sliding doors, comprising a pair of doors, a rack carried by each of said doors, and a pinion meshing with said racks whereby the motion of one is transmitted to the other, and a carrying device for said pinion, said carrying device being slidably mounted and having lateral movement relatively to the line of movement of said racks.

4. An improvement in sliding doors, comprising a pair of doors, a rack carried by each of said doors, and a pinion meshing with said racks whereby the motion of one is transmitted to the other, and a carrying device for said pinion, said carrying device including a cage slidably movable in a bracket and means

carried by said cage to hold its racks in mesh with said pinion.

5. An improvement in sliding doors, comprising a pair of doors, a rack carried by each of said doors, and a pinion meshing with said racks whereby the motion of one is transmitted to the other, and a carrying device for said pinion, said carrying device including a cage slidably movable in a bracket and rollers carried by said cage to hold the racks in mesh with said pinion.

6. An improvement in sliding doors and the like comprising a pair of doors, a **U**-shaped rack attached to each of said doors and a pinion for mutual engagement with said racks.

7. An improvement in sliding doors and the like comprising a pair of doors, a **U**-shaped rack attached to each of said doors and a barrel-shaped pinion for mutual engagement with said racks.

Signed at New Britain, Connecticut, this 13th day of January, 1902.

GEORGE B. PICKOP.
